UNITED STATES PATENT OFFICE

148,992

DESIGN FOR A JEWEL BOX OR THE LIKE

Herbert Jacobson, New York, N. Y.

Application April 12, 1947, Serial No. 138,328

Term of patent 14 years

(Cl. D86—9)

To all whom it may concern:

Be it known that I, Herbert Jacobson, a citizen of the United States, residing at New York, in the county and State of New York, have invented a new, original, and ornamental Design for a Jewel Box or the like, of which the following is a specification, reference being made to the accompanying drawing, forming a part thereof.

Fig. 1 is a front-elevational view of a jewel box or the like, showing my new design;

Fig. 2 is a side-elevational view thereof;

Fig. 3 is a top plan view thereof; and

Fig. 4 is a cross-sectional view thereof with cover in open position.

I claim:

The ornamental design for a jewel box or the like, as shown.

HERBERT JACOBSON.
